AUTOMATIC TUNING ARRANGEMENT

Nelson P. Case, Great Neck, N. Y., assignor to
Hazeltine Corporation, a corporation of Delaware

Application October 22, 1937, Serial No. 170,318

9 Claims. (CL 250—20)

This invention relates to automatic tuning arrangements for carrier-wave signal-receiving apparatus and, while of general application, it is particularly suitable for tuning wave signal receivers utilizing automatic amplification control.

In many installations of carrier-wave signal-receiving apparatus, it is desirable to incorporate a motor driven tuning arrangement as a part of the apparatus. Mechanical systems for remote tuning are, in general, unsatisfactory because of the mechanical complexity of the apparatus linking the tuning units of the receiver with the control device. This is particularly true of remote tuning arrangements such as required for auto-
mobile receivers. For this reason, a motor driven control has been used extensively comprising a push-button controlled electrical motor or equivalent device for operating the tuning unit of the receiver. When such a motor is used, a satisfactory speed of tuning between stations is generally found to be very much too fast for accurate tuning in the vicinity of the desired station, resulting in an over-running of the station. On the other hand, if a slow speed motor is used, it is generally unsatisfactory because of the time required to tune between stations which are widely separated on the dial of the receiver.

It is an object of the invention, therefore, to provide an automatic tuning control apparatus for speedily and accurately tuning a carrier-wave signal-receiving device.

It is another object of the invention to provide a motor operated tuning control for tuning a radio receiver which operates at a relatively high speed between stations but at a relatively low speed in the vicinity of stations having a relatively great signal strength.

In accordance with the invention, a carrier-wave receiving apparatus having automatic amplification control is provided with a motor for driving the tuning unit of the receiver and means for remotely controlling the motor for either direction of rotation. Means are provided for varying the speed of the motor in accordance with the amplitude of the received signal. This means is preferably dependent upon the direct current component of the space current of one or more tubes of the receiver which are subjected to automatic amplification control. Thus, when the receiver is being tuned in the vicinity of a station having a relatively strong signal, the direct space current of the tubes subject to automatic amplification control is less and the speed of the motor is correspondingly reduced. In one embodiment of the invention, means are provided dependent

upon the speed-reducing means for the tuning motor, for muting the receiver during a portion of the tuning operation.

The novel features which are believed to be characteristic of this invention are set forth with particularity in the appended claims. The invention itself, however, both as to its organization and operation, together with other objects and advantages thereof, will best be understood by reference to the following specification taken in connection with the accompanying drawing, in which Figs. 1 and 2 are circuit diagrams, partially schematic, of a radio broadcast receiver incorporating the invention in somewhat different forms.

Referring more particularly to Fig. 1 of the drawing, there is illustrated one form of the tuning arrangement embodied in a radio receiver of the well-known superheterodyne type. Briefly described, the receiver comprises a radio-frequency amplifier and selector 10 of one or more stages, connected to an antenna-ground circuit 11 and coupled to a frequency-changing unit or oscillator-modulator 12. The radio-frequency amplifier 10 may be of any conventional type and includes one or more tunable selector circuits, each provided with an adjustable tuning condenser 13, and one or more vacuum tubes 14. Similarly, the frequency-changing unit 12 may be of any conventional type and includes in its radio-frequency selector circuit and its local oscillator circuit adjustable tuning condensers, represented generally by condenser 15. A modulator tube 16 is included in frequency-changing unit 12. Connected in cascade to the output circuit of the frequency-changing unit 12 are an intermediate-frequency amplifier 17 of one or more stages, a detector and automatic amplification control-bias supply 19, an audio-frequency amplifier 21 of one or more stages, and a sound reproducer 22. The bias potential derived from the automatic amplification control source 19 may be applied to the tubes of one or more of the stages of the radio-frequency amplifier 10, the modulator tube 16, and to the tubes of one or more of the various stages of the intermediate-frequency amplifier 17 by way of conductor 20. It will be understood that only the direct current circuits and elements in the space discharge paths of tubes 14, 16, and 18, which are necessary to describe the present invention, are shown in the diagram and that the alternating current circuits of these tubes may be of a conventional design which is well understood in the art.

Considering, first, the operation of the receiver

as a whole, without regard to the details of the tuning arrangement of the invention, per se, a desired received signal wave is selected and amplified in the radio-frequency amplifier 16 and is converted into a modulated intermediate-frequency signal by the frequency changer 12. The signal as thus converted is further amplified in amplifier 17 and rectified by the detector 19, thereby deriving the audio frequencies of modulation which are, in turn, amplified in the audio-frequency amplifier 21 and reproduced in the sound reproducer 22. The amplification of the received signal is subject to automatic control by the control-bias potential derived from the source 18 according to the manner well understood in the art.

Referring now more particularly to the details of the tuning arrangement of the invention, there is provided an alternating current motor 20 M having a series field 23, the motor M being mechanically coupled to and preferably positioned adjacent the tuning condensers 13 and 15. The motor is driven from a source of supply 24 and remotely controlled through a control station indicated generally at 25. The control station 25 may be positioned at a convenient location on the receiver cabinet or at a point remote from the receiver and comprises two normally open double-contact push-button switches F and R to provide, respectively, for forward and reverse rotation of the motor. The switches F and R are connected as ordinary reversing switches for the series field 23 of the motor M and are mechanically interlocked by means of the bar 26 to prevent simultaneous operation of both switches.

There is provided a saturable reactor 27 having an iron core 28 of three legs, two alternating current windings 29 and 30, which are connected in series with each other and the motor M, and a direct current winding 33 disposed on the middle leg of the iron core 28 and shunted by a condenser 32. The direct space current of the tubes 14, 16, and 18 is supplied from a suitable source of direct current, such as battery 31. Windings 29 and 30 are so poled that alternating currents in these windings induce potentials of opposite polarity in the winding 33.

In considering the operation of the tuning arrangement described above, it will be seen that the tuning units 13 and 15 can be controlled in either direction by means of the reversible motor M from the remote control station 25 by operation of one of the push buttons F or R for the desired direction of rotation. Thus, if the push button F is operated to close its contacts, the field 23 is connected in series with motor M and windings 29 and 30 across the supply source 24. If the push button R is operated, the field 23 is connected with opposite polarity in series with windings 29 and 30 and the armature of motor M across the supply source 24. However, direct space currents of tubes 14, 16, and 18 vary widely with variations in the automatic amplification control bias applied to the tubes. Thus, when the receiver is tuned to a strong signal, the bias applied to the tubes is such that direct current of relatively small values flows through the winding 33 from the source of supply 31. At this time iron core 28 is not saturated, and the active drop across the windings 29 and 30 results in a relatively small voltage being applied to the motor M, so that it rotates relatively slowly. If the receiver is tuned to a station having a weak signal strength, the direct current in the winding 75 33 is correspondingly increased, saturating the

core 28 and thereby reducing the reactance of the windings 29 and 30 and increasing the motor speed. Thus, it will be seen that the circuit of Fig. 1 provides an arrangement whereby the tuning condensers 13 and 15 can be operated in either direction to tune toward a desired station on the dial. The tuning operation is relatively rapid between stations, but as a station of appreciable signal strength is approached, the speed of the motor M decreases so that it is relatively easy to stop the motor quickly by releasing the button F or R to tune the receiver accurately to the desired signal. An auxiliary switch 40 may be provided, if desired, for the purpose of short-circuiting the windings 29 and 30 when it is desired to tune to a station at a remote point on the dial, thus to prevent the normal operation of the invention to slow the speed of the motor at each of the intervening stations of strong signal strength.

Another embodiment of the invention is disclosed in Fig. 2 and is very similar in its operation to that of the circuit of Fig. 1. Corresponding parts of the two systems have been given the same reference numerals. The system of Fig. 2 differs from that of Fig. 1 primarily in the fact that a resistor 34 is inserted in series with the motor M when it is desired to reduce its speed, in lieu of the saturable reactor 27 of Fig. 1. The motor M of Fig. 2 may be suitable for operation on either alternating or direct currents. In this embodiment of the invention, a relay, having a coil 35 connected in series with the space current paths of tubes 14, 16, and 18, is provided with contacts 36 for inserting the resistor 34 in the motor circuit. A second normally open set of contacts 37 is provided on the relay and connected in the audio-frequency channel of the receiver in such manner that, when closed, loud-speaker 22 is silenced. The relay 35-36-37 is preferably so designed that there is a small differential between the value of its pick-up and drop-out current, so that the relay operates to change the speed of the motor at approximately the same point whether the receiver is being tuned away from or toward a desired strong signal.

In considering the operation of the circuit of Fig. 2, it will be seen that the contacts 36 and 37 of the relay open when the receiver is being tuned in the vicinity of a signal having an appreciable signal strength. When the winding 35 is energized, the contacts 36 short-circuit the resistor 34 in the motor circuit to increase its speed. Simultaneously, the contacts 37 mute the audio-frequency amplifier 21 for silent tuning. It is believed that, with the description given above in connection with Fig. 1, the operation of the circuit of Fig. 2 will be readily apparent and that no further description thereof is necessary.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A carrier-wave signal receiver comprising a stage of amplification subject to automatic amplification control, a tuning unit, a motor for operating said tuning unit, manual control means for said motor, and means for changing the speed of

operation of said tuning unit to a low but appreciable speed in response to the tuning of the receiver through a signal of a predetermined amplitude comprising means for controlling the speed of operation of said tuning unit in accordance with the magnitude of the bias of said amplification control.

2. A carrier-wave signal receiver comprising a tuning unit, a motor for operating said tuning unit, manual control means for said motor, means for developing an automatic volume control bias, and means for changing the speed of operation of said tuning unit to a low but appreciable speed in response to the tuning of said receiver through a signal of predetermined amplitude comprising means responsive to said bias for controlling the speed of operation of said tuning unit in accordance with the magnitude of said bias.

3. A carrier-wave signal receiver comprising a stage of amplification comprising a vacuum tube, means for automatically controlling the amplification of said tube, a tuning unit, a motor for operating said tuning unit, manual control means for said motor, and means for changing the speed of operation of said tuning unit to a low but appreciable speed in response to the tuning of the receiver through a signal of predetermined amplitude comprising means for controlling the speed of operation of said tuning unit in accordance with the average space current of said tube.

4. A carrier-wave signal receiver comprising a stage of amplification subject to automatic amplification control, a tuning unit, a motor for operating said tuning unit, manual directional control means for said motor, means for changing the speed of said motor to a low but appreciable speed in response to the tuning of the receiver through a signal of predetermined amplitude comprising an impedance in circuit with said motor, and means for controlling said impedance in accordance with the magnitude of the bias of said amplification control.

5. A carrier-wave signal receiver comprising a stage of amplification subject to automatic amplification control, a tuning unit, an alternating current motor for operating said tuning unit, manual control means for said motor, means for changing the speed of said motor to a low but appreciable speed in response to the tuning of the receiver through a signal of predetermined amplitude comprising a saturable reactor in circuit with said motor, and means for controlling the saturation of said reactor in accordance with the magnitude of said amplification control.

6. A carrier-wave signal receiver comprising a

stage of amplification subject to automatic amplification control, a tuning unit, a motor for operating said tuning unit, manual directional control means for said motor, means for changing the speed of said motor to a low but appreciable speed in response to the tuning of the receiver through a signal of predetermined amplitude comprising an impedance in said motor circuit, and means comprising a relay operated in accordance with the magnitude of said amplification control for short-circuiting said impedance, thereby to vary the speed of said motor.

7. A carrier-wave signal receiver comprising a stage of amplification subject to automatic amplification control, a tuning unit, a motor for operating said tuning unit, manual directional control means for said motor, means for changing the speed of said motor to a low but appreciable speed in response to the tuning of the receiver through a signal above a predetermined amplitude comprising an impedance in circuit with said motor, means for controlling said impedance in accordance with the magnitude of said amplification control, and means comprising said means for controlling said impedance for muting said receiver.

8. A carrier-wave signal receiver comprising a stage of amplification subject to automatic amplification control, a tuning unit, a motor for operating said tuning unit, manual directional control means for said motor, means for changing the speed of said motor to a low but appreciable speed in response to the tuning of the receiver through a signal of predetermined amplitude comprising an impedance in circuit with said motor, means comprising a relay operable in accordance with the magnitude of said amplification control for short-circuiting said impedance, thereby to vary the speed of said motor, and means comprising said relay for muting said receiver.

9. A carrier-wave signal receiver comprising a tuning unit, a motor for operating said tuning unit, manual control means for said motor, means for developing an automatic bias control, means for utilizing said bias control to control the amplification in said receiver, and means for changing the speed of operation of said tuning unit to a predetermined low fixed speed in response to the tuning of the receiver through a signal of greater than a predetermined amplitude comprising means responsive to said bias for controlling the speed of operation of said tuning unit in accordance with the magnitude of said bias.
